KICKING TEE

Clyde V. Martin, Los Angeles, Calif.

Application July 12, 1954, Serial No. 31,379

Term of patent 3½ years

(Cl. D34—5)

I claim:

The ornamental design for a kicking tee, substantially as shown.
